UNITED STATES PATENT OFFICE.

ARTHUR JOHN NASH, OF NEW YORK, N. Y.

DESIGN FOR A FLOWER-HOLDER.

50,664.

Specification for Design.

Patented Apr. 24, 1917.

Application filed February 3, 1917. Serial No. 146,528. Term of patent 7 years.

To all whom it may concern:

Be it known that I, ARTHUR JOHN NASH, a citizen of the United States, residing in the city of New York, Flushing, borough of Queens, in the county of Queens and State of New York, have invented a new, original, and ornamental Design for Flower-Holders, of which the following is a specification, reference being had to the accompanying drawing, forming part thereof.

Fig. 2 is a side elevation of the same.

I claim:

The ornamental design for a flower holder, as shown.

ARTHUR JOHN NASH.
